US00D585448S

(12) **United States Design Patent**
Kawaguchi et al.

(10) **Patent No.:** US D585,448 S
(45) **Date of Patent:** ** Jan. 27, 2009

(54) **MEMORY CARD**

(75) Inventors: **Tomonori Kawaguchi**, Tokyo (JP); **Masahiro Takase**, Tokyo (JP); **Minako Eguchi**, Tokyo (JP); **Jun Ebisawa**, Tokyo (JP); **Chikako Hasegawa**, Tokyo (JP); **Yoshinobu Higuchi**, Tokyo (JP)

(73) Assignee: **Sony Corporation**, Tokyo (JP)

(**) Term: **14 Years**

(21) Appl. No.: **29/300,057**

(22) Filed: **Feb. 15, 2008**

(30) **Foreign Application Priority Data**

Aug. 24, 2007 (JP) D2007-023008

(51) **LOC (9) Cl.** **14-02**

(52) **U.S. Cl.** **D14/435**

(58) **Field of Classification Search** D14/435, D14/356, 242, 436, 433, 474, 240, 496, 385, D14/358; 360/97.01, 685, 686, 752, 737, 360/732, 784, 803; 439/135, 144, 139-141, 439/147, 136, 638, 518, 131; 365/51, 63, 365/131; 710/52, 300, 313; 711/115, 103, 711/154, 161-162; 70/58; 323/210; 713/186, 713/1; 382/124; 235/492; D13/147

See application file for complete search history.
